REGULATOR

Walter S. Dickson, Upper Montclair, N. J.

Application August 14, 1936, Serial No. 96,028
Renewed December 14, 1939

12 Claims. (Cl. 137—153)

This invention relates to a regulator by means of which a large variety of control members can be utilized for a large variety of purposes, and in different sorts of installations.

5 The regulator is particularly useful for varying a continuous flow of fluid, either liquid or gaseous, in response to changes or impulses in the medium to be controlled. The variation in the flow of the fluid caused by this regulator is capable of causing 10 control mechanisms of different sorts already known to control such things as pressure, vacuum, rate of flow of steam, air or other fluids, temperature, speed, liquid level, density of liquids, feed lines, voltage, humidity, etc.

15 In carrying out the invention, pressure or vacuum or both can be used to operate a lever whose fulcrum can be shifted. This lever carries a closure member for the end of a pipe, by means of which the flow as well as the pressure of fluid 20 in this pipe is regulated. The changes in the pressure in this pipe operates control mechanism for different purposes, and changes in the medium to be controlled operates the regulator.

The invention will be understood from the 25 description in connection with the accompanying drawing, in which Fig. 1 is a section along the line 1—1 of Fig. 2, showing an illustrative embodiment of the invention; Fig. 2 is a plan view with parts removed; Fig. 3 is a section along the 30 line 3—3 of Fig. 1; and Fig. 4 is a section through a type of motor that may be used in connection with the invention.

In the drawing, reference character 1 indicates a container that is preferably made of metal, such as brass, for example. It is provided with a 35 removable cover 2. A short section of pipe 3 is externally threaded at its upper end and is screwed into a threaded opening 4 in the cover 2. This pipe has its end that extends into the container 1 open, and a fluid is caused to flow through 40 this pipe from a convenient source. The fluid may be air from an air compressor or water from city mains for example and the source is preferably at substantially constant pressure, or a pressure regulator is used near the exit end of pipe 11. 45 An opening may be provided at any convenient place in the container 1 for escape of the fluid that enters through the pipe section 3. A nozzle 5 is provided at the open end of the pipe section 3, and a cleaner rod 6 is provided for the nozzle. This cleaner 6 may be a twisted rod for example. A hollow disk 7 is attached to the upper end of 50 the rod 6 by a spider with its rim resting upon an internal annular shoulder 8 in the pipe section 3 to limit the downward movement of the rod 6.

A compression spring 9 has its lower end resting upon the hollow disk 7 and the upper end of this spring bears against the end of a hollow plug 10 that is screwed into the inside of the pipe section 3.

A pipe 11 leads from the source (not shown) of fluid under pressure and a branch 12 leads from this pipe 11 to the diaphragm motor as shown in Fig. 4. An adjustable restriction or throttle plug 11' is provided near the exit end of pipe 11. A cleansing extension 6' extends from the upper end 10 of rod 6 to the space at the end of plug 11' for cleaning this space.

A pipe or pipes lead to the Sylphons or bellows 13 and/or 14 from locations where the medium to be controlled undergoes variations and is to be 15 regulated by this regulator. Screw plugs 17 and 18 are provided in the pipes 15 and 16 to adjust or restrict the size of openings in these pipes. Nipples 19 and 20 connect the Sylphons 13 and 14 to the pipes 15 and 16 and these nipples are rigidly 20 fixed in the cover 2 to keep the upper ends of the Sylphons in fixed positions. The nipples 19 and 20 may be fixed in position by being soldered or welded in the cover or by being screw threaded and screwed into screw threaded openings in the 25 cover. Cleaning pins 17' and 18' (Fig. 2) may be attached to the bottoms of the Sylphons 13 and 14 and extend into the spaces between the ends of the screw plugs 17 and 18 and the inside walls of the pipes 15 and 16, if desired. The lower movable ends of the Sylphons 13 and 14 are connected 30 pivotally by connections 21 and 22 to lugs 23 and 24 on the lever 25. A slideable fulcrum 26 is provided for the lever 25. This fulcrum is triangularly shaped in cross section or is shaped like a 35 prism with a flat side resting against and slideable upon the bottom of container 1, with the lever 25 resting upon its upper edge, which serves as a fulcrum for this lever. A screw threaded opening 27 is provided through the fulcrum 26 and a 40 threaded rod 28 extends through this opening 27. The end walls of the container 1 are provided with bearings 29 and 30 in which the reduced ends 31 and 32 of the rod 28 are journaled. The rod 28 is provided with a screw driver slot 33 in one end 45 so that it can be turned from the outside of the container 1 to shift the fulcrum 26.

A compression spring 35 rests against a dished disk 36 that is located near one end of the lever 25, and the other end of this spring bears against 50 a similar disk 37. A screw 38 passes through a threaded hole 40 in the cover 2 and serves for adjusting the tension of the spring 35. A lock nut 40 is provided for the screw 38.

A pair of adjustable stops 41 and 42 is provided 55

near each end of the lever 25. These stops are conveniently made adjustable by being made of screws that pass through threaded openings in the bottom of the container 1.

5 A spring 43, consisting of a short flat strip of resilient metal, is attached at one end to the lever 25 in any convenient manner, as by soldering, welding or riveting the same, so as to be firmly secured in position, so that it springs away from 10 the reduced portion 43' of the lever 25 against which this spring 43 rests when it is pressed down. The spring 43 is for closing the nozzle 5 gradually when the left hand end of the lever 25 rises. When the end of the nozzle is closed the 15 rod 6 and extension 6' are simultaneously moved longitudinally and removes any dirt that may have collected in the nozzle or at the end of the throttle 11'.

The operation of this regulator will be described in connection with the motor shown in Fig. 4 for regulating the steam pressure in the pipe 58, but it is to be understood that this regulator is suitable for use with numerous other sorts of control mechanisms.

25 For example, the pressure of the steam passing beyond the valve 59 in the direction of the arrow may be kept substantially constant with this regulator. A branch pipe 60 from the pipe 58 is connected to one of the Sylphons 13 and 14, so 30 that the pressure inside the Sylphon will vary with variations of the steam pressure to the right of the valve 59. A fluid from any convenient source under substantially constant pressure passes through the pipe 11 and a jet thereof 35 passes out of the nozzle 5. A branch 12 extends from the pipe 11 to the motor shown in Fig. 4 which is a diaphragm motor. It comprises a housing or container 51 that is fixed in position and is divided into two compartments 52 and 53 40 by a flexible diaphragm 50 that extends through it. A rod 54 is connected, as indicated at 55, to the diaphragm 50 and is slideable through an opening 56 in the housing 51. A lever or other convenient mechanism is connected to the rod 54 45 in such a way that movement of this rod opens and closes the valve 59 in the pipe 58. Various sorts of mechanical and electrical devices are already well known for such purposes and since 50 the same constitute no part of the present invention they will not be described in detail.

When the pressure in the pipe 58 to the right of the valve 59 decreases, the pressure in the Sylphon 13 or 14 to which the pipe 60 is connected decreases so that the compression spring 35 turns 55 the lever 25 clockwise, thereby closing or partially closing the nozzle 5 as the spring 43 is brought into contact with or near to the end of the pipe 3. The closing or partial closing of this nozzle increases the pressure of the fluid in the pipe 11 and consequently increases the pressure in the pipe 12. This increase of pressure in the pipe 12 is transferred to the compartment 52 in the diaphragm motor (Fig. 4), thus moving the diaphragm 50 and rod 54 downwardly, thus opening 60 the valve 59 further by the connections above referred to. The opening of the valve 59 permits more steam to pass and thereby returns the pressure at the branch pipe 60 to the desired point. An increase in this pressure causes the lever 25 65 to move in the anti-clockwise direction, thus opening the nozzle 5 more, which in turn causes the valve 59 to be closed to some extent, as will be understood.

Either one of the Sylphons 13 or 14 may be 75 used for opposing the spring 35, while the other

one is used as a compensating device or to avoid hunting.

One of the Sylphons 13 and 14 may be connected to a vacuum that is to be controlled. In such a case the fulcrum 26 is shifted to the right of spring 35. The operation is similar to that already described, or the Sylphons may be connected to air under pressure in a zone whose temperature is to be controlled from the variation in temperatures operating mechanism similar to the manner already described, and so on, for other conditions to be controlled, as will be understood.

The adjusting screws 41 and 42 limit the extent of travel of the lever 25 in opposite directions and are also available for lifting the lever 25 off 15 of the fulcrum 26 when it is desired to shift this fulcrum, by turning the screw threaded rod 28.

When the fulcrum 26 is shifted to the left to the dotted line position, the Sylphons work differentially, and, when it is shifted to the right 20 of the dotted line position, it is necessary to use vacuum in one of the Sylphons to turn the lever 25 clockwise. The dished disks 36 and 37 provide a convenient way for substituting springs 35 25 of different characteristics.

I claim:

1. A regulator comprising a conduit connected to a source of substantially constant pressure fluid and having an outlet open to the atmosphere, a pivoted lever adapted to contact with said outlet for varying the size thereof, a shiftable fulcrum for said lever, a fluid operated member communicating with a medium to be controlled and cooperating with said lever on one side of said fulcrum to turn said lever, and fluid 35 means responsive to pressure in said conduit for controlling said medium.

2. A regulator comprising a conduit connected to a source of substantially constant pressure fluid and having an outlet open to the atmosphere, a restriction in said conduit between said source and said outlet, a pivoted lever adapted to contact with said outlet for varying the size thereof, a shiftable fulcrum for said lever, a fluid operated member communicating with a medium to be controlled and cooperating with said lever on one side of said fulcrum to turn said lever, and fluid motor means responsive to pressure in said conduit for controlling said medium.

3. A regulator comprising a conduit connected to a source of substantially constant pressure fluid and having an outlet open to the atmosphere, a pivoted lever adapted to contact with said outlet for varying the size thereof, a shiftable fulcrum for said lever, a fluid operated member communicating with a medium to be controlled and cooperating with said lever on one side of said fulcrum to turn said lever, fluid motor means responsive to pressure in said conduit for controlling said medium, and means to lift said lever off said fulcrum.

4. A regulator comprising a conduit connected to a source of substantially constant pressure fluid and having an outlet open to the atmosphere, a pivoted lever adapted to contact with said outlet for varying the size thereof, a shiftable fulcrum for said lever, a bellows communicating with a medium to be controlled and cooperating with said lever on one side of said fulcrum to turn said lever, and fluid motor means responsive to pressure in said conduit for controlling said medium.

5. A regulator comprising a conduit connected to a source of substantially constant pressure

- fluid and having an outlet open to the atmosphere, a pivoted lever adapted to contact with said outlet for varying the size thereof, a shiftable fulcrum for said lever, a fluid operated member communicating with a medium to be controlled and cooperating with said lever on one side of said fulcrum to turn said lever, a spring cooperating with said lever on the other side of said fulcrum from said fluid operated member, 5 and fluid motor means responsive to pressure in said conduit for controlling said medium.
6. A regulator comprising a conduit connected to a source of substantially constant pressure fluid and having an outlet open to the atmosphere, a pivoted lever adapted to contact with said outlet for varying the size thereof, a shiftable fulcrum for said lever, means for shifting said fulcrum along said lever, a fluid operated member communicating with a medium to be controlled 10 and cooperating with said lever on one side of said fulcrum to turn said lever, and fluid motor means responsive to pressure in said conduit for controlling said medium.
7. A regulator comprising a conduit connected 15 to a source of substantially constant pressure fluid and having an outlet open to the atmosphere, a pivoted lever adapted to contact with said outlet for varying the size thereof, a shiftable fulcrum for said lever, means including a threaded rod for shifting said fulcrum along said lever, a fluid operated member communicating with a medium to be controlled and cooperating with said lever on one side of said fulcrum to turn said lever, and fluid motor means responsive 20 to pressure in said conduit for controlling said medium.
8. A regulator comprising a conduit connected 25 to a source of substantially constant pressure fluid and having an outlet open to the atmosphere, a pivoted lever adapted to contact with said outlet for varying the size thereof, a shiftable fulcrum for said lever, an adjustable stop for said lever on each side of said fulcrum, a fluid operated member communicating with a medium to be controlled and cooperating with said lever on one side of said fulcrum to turn said lever, and fluid motor means responsive to pressure in 30 said conduit for controlling said medium.
9. A regulator comprising a conduit connected 35 to a source of substantially constant pressure fluid and having an outlet open to the atmosphere, a pivoted lever adapted to contact with said outlet for varying the size thereof, a shiftable fulcrum for said lever, a spring pressing against said lever, means for shifting said fulcrum to opposite sides of said spring, a fluid operated member communicating with a medium to be controlled and cooperating with said lever on one side of said fulcrum to turn said lever, and fluid motor means responsive to pressure in 40 said conduit for controlling said medium.
10. A regulator comprising a conduit connected 45 to a source of substantially constant pressure fluid and having an outlet open to the atmosphere, a pivoted lever having a flexible member adapted to contact with said outlet for varying the size thereof, a shiftable fulcrum for said lever, a fluid operated member communicating with a medium to be controlled and cooperating with said lever on one side of said fulcrum to turn said lever, and fluid motor means responsive to pressure in 50 said conduit for controlling said medium.
11. A regulator comprising a conduit adapted to contain fluid under pressure and having an outlet to the atmosphere, a pivoted lever in proximity to said outlet for varying the rate at which fluid can pass through said outlet, means operated by a medium to be controlled cooperating with said lever to change its position, a spring pressing against said lever on one side of its pivot, and fluid motor means responsive to change of pressure in said conduit for controlling said 55 medium.
12. A regulator comprising a conduit connected to a source of substantially constant pressure fluid and having an outlet open to the atmosphere, a pivoted lever adapted to contact with said outlet for varying the size thereof, a fluid operated member communicating with a steam chamber whose pressure is to be controlled and cooperating with said lever on one side of its fulcrum to turn said lever, and fluid motor means responsive to pressure in said conduit for controlling the pressure in said steam chamber.

WALTER S. DICKSON.
